UNITED STATES PATENT OFFICE.

ALEXANDER D. JOSLIN, OF CHICAGO, ILLINOIS.

AGENT'S TICKET-PUNCHING MACHINE.

No. 806,262.

Specification of Letters Patent.

Patented Dec. 5, 1905.

Application filed January 21, 1905. Serial No. 242,079.

To all whom it may concern:

Be it known that I, ALEXANDER D. JOSLIN, a citizen of the United States, residing in Chicago, in the county of Cook and State of Illinois, have invented a new and useful Improvement in Agents' Ticket-Punching Machines, of which the following is a specification.

In combination with the ticket shown herein this invention is designed to furnish a superior means of conducting ticket sales at railroad-stations. It obviates the necessity of keeping on hand a large stock of different forms of tickets in order to make sales to any and all stations on the line and at the same time it imparts to the tickets the most approved features designed to prevent fraud by outside parties, as it is adapted to indicate upon the ticket by one operation all the various particulars required as to date of sale, class or kind of ticket, and the approximate rate at which it is sold, and these indications are made in such a way as to render them practically unalterable.

The invention is adapted to punch the date of sale on one margin of each coupon and agent's stub and to make a similar cancellation of the class, rate, and possibly other data on the opposite margin of the ticket, while the ticket coupon and stub are folded on transverse tearing-lines, so that the agent is able to prepare the ticket quickly and separate it from the stub, and the ticket thus issued will be little liable to subsequent fraudulent manipulation. The punches made upon each cancellation by the invention show as notches or recesses in the margins of the coupon and stub, and this renders the plugging of such cancellations with a view of extending the time limit or changing the terms or value of the ticket reasonably sure of detection, as aside from the great difficulty of plugging the margin of a ticket bearing punched recesses any plugging of such recesses on the tearing on folded lines would surely be discovered by the conductor when he separates the coupon from the ticket upon presentation to him for passage. The punching of the date of sale obviates the use of the common dating-stamp and is more convenient for auditing than the dating-stamp impression, as the latter is usually placed on the back of the ticket. Furthermore, as local tickets are generally limited to continuous passage, commencing on the date stamped on the back, the changing of the stamped impression, which is not at all difficult, is all

that is necessary to make the ticket good for any later date desired.

My invention is intended, primarily, for use in connection with local tickets for either one-way or round-trip passage. The ticket shown here is of the kind known as "train-check" or "auditor's-stub" one-way or single-passage ticket, inasmuch as it provides a contract-coupon or auditor-stub to be taken up by the first conductor. This coupon or stub being a counterpart of the succeeding passage-coupon or train-check which covers the passage through to destination is returned to the auditor's office and insures a proper check on the selling agent in case the passage-check or train-coupon does not come in.

The accompanying drawings show at Figure 1 a side elevation of my improved punching-machine. Fig. 2 is an enlarged longitudinal section. Figs. 3 and 4 are sections on the lines 3 3 and 4 4, respectively, of Fig. 2. Fig. 5 is a horizontal section. Fig. 6 is a section on the line 6 6 of Fig. 5. Fig. 7 is a transverse section of the operating - lever. Fig. 8 is a partial side elevation enlarged and partly in section. Fig. 9 shows the ticket in an extended or unfolded condition, and Fig. 10 shows it as folded. Figs. 11 and 12 are sections, and Fig. 13 a side elevation, of one of the punches.

In said drawings, 10 represents a frame rectangular in shape and supporting a casing 11, in which the operating parts of the machine of the invention are located. The casing is secured to the frame 10 by vertical screws 12, passing through the corner-columns 13, cast upon the casing, into similar columns upon the frame. The ticket, which is first folded as shown in Figs. 3, 4, 6, and 10, is inserted into the casing at the opening 14, formed between an upper plate 15, movably attached to plate 28, and a lower plate 16, supported upon the frame and secured thereto by screws 17. The entrance to the opening is at the end of the machine and is provided with an outward-projecting shelf at lower surface which serves as a guide for the folded ticket and assists in quickly inserting same, and the ticket when positioned therein appears, as clearly shown at Figs. 3, 4, and 6, in readiness to be operated upon by the machine, the ticket and opening corresponding in size and shape. The end of plate 15 at the end where the ticket enters is preferably turned up, as shown in the drawings, in order that the ticket may not be caught by it. On

top of the casing is a lever 20, mounted upon and rigid with a pivot 21 and having a cam-slot 22 formed in its base, engaging a pin 23, preferably provided with a bushing 24 and supported upon uprights 25, formed on or attached to a longitudinal bar 26. This bar is supported at its ends upon toggles 27, and the movement imparted to the bar by the cam-lever is adapted to straighten the toggles, 5 and thereby to depress the plate 28, which is vertically movable within the casing and is fitted to its interior. Centering-pins 29 are movably secured in the plate 28 and at their upper ends above said plate are provided with nuts 30. Between the plates 15 and 28 and surrounding the pins are springs 31, adapted to press downward the plate 15, thereby compressing the folds of the ticket, so that it will pass freely between the jaws of the sliding 10 punches. Along each of its longitudinal sides the movable plate 28 is slotted upon its under side with T-shaped slots, (shown at 33,) and movably positioned in each of these slots are male dies of the punches by which the desired data are punched in the ticket. Two 15 companion dies 34 and 35, supported in a head 36, fitting the slot, are preferably employed in each punch. Of these the larger one 34 is located so as to punch the folded edge of the ticket, and the smaller one makes a minute opening in the body of the ticket in immediate proximity to the recess formed by the larger one. This double feature of the punch is not essential to the main feature of the invention; but it is desirable because of the additional security it affords against fraud and because it indicates the location of the larger punched recess in the margin of the ticket should the same be torn off. The lower ends 20 of said dies are fitted into correspondingly shaped and sized vertical openings in the female dies 37, as plainly shown at Fig. 6, and these latter dies also serve as a means of adjusting the punches longitudinally of the ticket, as they are themselves movable and carry the male dies along with them. Thus, 25 as seen in Fig. 8, one of the dies 37 is adjusted with its pointer 45 at the figure "9," so that the punch of which said die forms a part will operate opposite that figure upon the ticket; but it may be moved so as to bring the pointer under any other figure. The under edges of the casing are recessed, as shown at 38, and the dies 37 are provided with spring-pins 39, adapted to engage these recesses and to stop the punches in their adjusted positions, there being one of the recesses 38 for each position to which the several punches 30 may be moved. The body or frame of the dies 37 projects outside of the machine, so that they may be conveniently taken hold of by the ticket agent and adjusted to any desired position, and they move between the bottom edge of the casing and the top edge of the frame and are confined in position by the in-

dicating-plates 40, which are located above the dies, and guide-plates 41, located below them, these plates entering slots formed in the body of the dies 37 above and below, as plainly shown at Figs. 3 and 6. At their inner ends the dies 37 are slotted horizontally in the plane of the opening 14, as seen at 46, so that the margin of the ticket can enter them, and thus be in position under the dies 34 and 35. That portion of the dies 37 below the slots 46 acts as a countering device to said dies 34 and 35. The latter are preferably provided with ledges 47, extending under the plate 16, to prevent "tipping" and too much friction of punch-head in the T-slots of 80 plate 28.

From the description above given it will be seen that the punches employed in my machine, of which seven are shown, (there may be more or less,) each consists of a T-head carrying the plungers or male dies and a lower slotted body or frame, the slot dividing the body or frame into upper and lower jaws 48 and 49, both provided with openings to receive the plungers, so that the upper jaw 90 serves as a guide to the plungers and the lower jaw as a counter-die, the T-head in which the plungers are fixed being movably inserted in a longitudinal slot in the head-plate, which is raised and lowered by the lever. The sides 95 of the punch-jaws 48 and 49, upon which the ticket first enters, is beveled, as clearly shown at Fig. 11, so that it not only will not catch the ticket, but, on the contrary, will guide it in its inward movement into the slot 46 between the jaws. The vertical wall at the back of the slot positions the ticket so that the larger plunger cuts out only about two-thirds of its diameter from the edge of the ticket, thus forming notches in the margin instead of 105 holes in the body of the ticket.

Below the punches the supporting-frame is recessed longitudinally, as plainly shown, and in these recesses are fitted removable drawers 42, adapted to catch the punchings from the tickets. These drawers are provided at one end with knobs 43, whereby they may be drawn out and emptied. The plates 40 are provided with the indicating figures or other characters desired and to correspond with or serve as an index to those upon the ticket, so that by adjusting the punches to the proper figure or character the ticket will be punched at the corresponding figure or character; but the same figures upon the plate may be used to indicate the different things on different tickets. The cam-lever is provided with retracting-springs 44, as shown at Fig. 7.

The ticket used with this punching-machine is preferably that indicated at Figs. 9 and 10 and consists of three sections, one section forming the agent's stub, another the train-check, and another the contract-coupon. Upon one side of the agent's stub there are figures and characters indicating the year, month, 120 and day, and upon the other side there are figures and characters indicating the year, month, 130

and the days of the month, and on the other side may be printed words indicating the class of fare and figures representing approximately the amount of fare paid. Upon the edge, 5 which is joined to the agent's stub, the train-check is provided with indicia of the class and of the approximate amount of fare corresponding to those on the agent's stub, and upon the side to which the contract-coupon is attached the train-check is printed with the 10 year, the month, and the day of the month. The contract-coupon, at the side by which it is joined to the check, is provided with the same marks as those upon the adjacent edge 15 of the check, while upon its other edge it is provided with class-indicators and figures representing the approximate amount of fare. After being folded at the division-lines between the sections, as shown in the drawings, 20 the ticket is inserted lengthwise in the opening 14 in the machine and the cam-lever is operated, and when taken out and unfolded the perforations in the different sections will have been made, as seen at Fig. 9. For convenience I have indicated the agent's stub at 25 50, the train-check at 51, and the contract-coupon at 52. The larger punch makes the opening 53 and the smaller one the openings 54. The larger punches should preferably 30 project outwardly beyond the folded edge of the ticket, so that the openings formed thereby in the different sections will be open at one side. It will be understood, however, 35 that the number of sections may vary from those shown and described—as, for instance, it may contain additional sections and be good for a round trip. The ticket shown is designed to have the destination written in the various sections; but tickets with printed 40 destinations may be used, in which case the auditor's stub or contract-coupon and the agent's stub, either or both, may be dispensed with. While it is not necessary that the ticket contain a plurality of sections or divisions or that 45 it be folded when punched, it is desirable that the data to be recorded by the punches be arranged along its margin, so that the punchings formed by the machine may be open upon one side, and thus prevent plugging of 50 same.

It will be noted that the machine is adapted by a single stroke of a single lever to impart to the ticket a large variety of data very essential in the keeping of accounts with the 55 agents and conductors and that it permits such changes in the machine as are necessary to enable it to record the data in an instant of time. It will also be noted that the sections or divisions of the ticket are all of the same 60 size, so that the folded ticket agrees with them in its dimensions, and the machine for punching the ticket is not required to be changed. It will still further be noted that the opening in the machine, in which the 65 ticket is inserted, is shallow vertically, so that

the ticket is as closely confined therein as is consistent with its easy insertion.

I claim—

1. The machine for punching railroad-tickets, having an opening in which the ticket may be inserted bodily; adjustable punches arranged to operate on opposite margins of the ticket, and a lever whereby all the punches may be operated at the same stroke. 70

2. The machine for punching railroad-tickets, having an opening in which the ticket may be inserted bodily, punches arranged to operate on opposite margins of the ticket and adjustable lengthwise of the same, and a lever whereby all the punches may be operated at 80 the same stroke. 75

3. The machine for punching railroad-tickets, having an opening in which the ticket may be inserted bodily, two series of punches, each of said series being adapted to operate on one of the margins of the ticket and each individual punch being independently adjustable lengthwise of the same, a vertically-movable plate supporting the punches, and a lever operating the plate. 85 90

4. The machine for punching railroad-tickets, having an opening in which the ticket may be inserted bodily, punches arranged to operate on the margins of the ticket and adjustable lengthwise of the same both individually and independently, a vertically-movable plate supporting the punches and a cam-lever and toggles for operating said plate. 95

5. The machine for punching railroad-tickets, having an opening in which the ticket may be inserted bodily, punches arranged to operate on the margins of the ticket and adjustable lengthwise of the same, a vertically-movable plate supporting the male dies of the punches, a cam-lever and toggles for operating the plate and a spring-pressed plate for compressing the ticket. 100 105

6. The machine for punching railroad-tickets, having an opening in which the ticket may be inserted bodily, punches arranged to operate on the margins of the ticket and adjustable lengthwise of the same, a vertically-movable plate supporting the male dies of the punches, a cam-lever and toggles for operating the plate, and a spring for returning the 110 lever and lifting the supporting-plate. 115

7. The machine for punching railroad-tickets, having a recess or opening in which the ticket may be inserted bodily, a series of punches for punching the date or other data 120 in the ticket, a vertically-movable support in which the punches are adjustably held, and can be adjusted between successive operations, a surrounding casing, the punches being adjustable from the outside of the casing, devices for stopping the punches in their adjusted positions, and a lever for operating the punch-support. 125

8. The combination with a surrounding casing, the vertically-movable slotted plate and 130

its actuating means, of the male dies slidably supported in the plate, and slidable counter-
5 ing-dies extending to the outside of the machine, and having openings at their inner ends to receive the male dies.

9. The combination with a surrounding casing the vertically-movable, slotted plate and its actuating means, of the male dies slidably supported in the plate, and slidable counter-
10 ing-dies extending to the outside of the machine and having openings at their inner ends to receive the male dies and also having horizontal slots admitting the tickets below the male dies.

15 10. The ticket-punching machine having a surrounding casing provided with an opening in which the ticket may be inserted bodily, and punching mechanism located within the casing and embracing dies with horizontal slots
20 for admitting the tickets, the entrances to said slots being beveled to insure the entrance of the tickets.

11. A machine for punching tickets having a casing, provided with an opening to admit
25 the body of the ticket, punching devices for punching the edge of the ticket and adjustable along such edge, said devices consisting of a main punch, a safety-punch in proximity thereto, and counter-dies.

30 12. The railroad-ticket-punching machine wherein are combined a surrounding casing and a series of punching devices located within

the casing and adjustable from the outside thereof, the casing having an opening adapted to admit the ticket and the punching devices 35 being arranged to operate upon the edge of the ticket.

13. The railroad-ticket-punching machine wherein are combined a surrounding casing and a series of punching devices located within 40 the casing and independently adjustable from the outside thereof, the casing having an opening admitting the ticket, and the punching devices being arranged to operate on the edge of the ticket.

14. The railroad-ticket-punching machine wherein are combined a surrounding casing and a series of punching devices located within the casing and independently adjustable from the outside thereof, the machine having an 50 opening admitting the ticket and in which it is closely confined, and the punching devices being arranged to operate on the edge of the ticket.

15. The railroad-ticket-punching machine 55 having a series of main or large punches for punching the date or other data desired, each of said punches being accompanied by a small punch adapted to form a safety-opening near the punching made by the large punch.

ALEXANDER D. JOSLIN.
